VARIABLE BAFFLE FOR TRANSLATING DEVICES

Frank J. Faltico, Minneapolis, Minn., assignor to
The Maico Company Incorporated, Minneapolis, Minn., a corporation of Minnesota

Application July 11, 1942, Serial No. 450,600

8 Claims. (Cl. 181—31)

This invention relates generally to improvements in translating devices, such as headphones, and more particularly to means for adjusting the baffle effect in such devices to thereby secure variations in frequency response.

The primary object of the invention is to provide means whereby the baffle effect of the usual headphone may be easily and quickly varied by permitting the passage of air waves between the front or outer side of the diaphragm and the back or inner side thereof. By this means the usual infinite baffle of such devices may be altered according to requirements and the frequency response varied by permitting at least the partial cancellation of unwanted frequencies in the audio range. Another object is to provide means of this nature in any extremely simple and practical form embodying simply an air passage-way communicating with the opposite sides of the diaphragm and a member arranged to adjustably open or close said passage-way and thereby control the volume of air passing therethrough.

These and other more detailed and specific objects will be disclosed in the course of the following specification, reference being had to the accompanying drawing, in which—

Fig. 1 is a diametrical section through a headphone type of translating device showing my invention embodied therein.

Fig. 2 is an inside elevation or plan view of the cap forming part of the structure of Fig. 1, showing the adjusting screw removed.

Fig. 3 is an enlarged, fragmentary cross sectional view illustrating the communication between opposite sides of the diaphragm.

Fig. 4 is a face or plan view of the body or case member forming part of the headphone, a portion thereof being shown in section.

Referring now more particularly and by reference characters to the drawing, a headphone type of translator or receiver is shown embodying essentially a casing or body member A having an annular shell B against the end of which the vibrating diaphragm C is placed and held by a cap D, said cap being screwed onto the body member as indicated at E (or otherwise fastened) and having a central opening F for the passage of sound waves formed by vibration of the diaphragm. An electromagnetic vibrating or driving motor or device G is secured to the body member A as clearly shown and includes wire wound pole pieces H disposed adjacent the diaphragm C.

The foregoing constitutes the usual construc-

tion of such units and no invention is herein claimed for such construction per se. In operation, the diaphragm C is vibrated by the mechanism G in accordance with the variations in electrical current flowing therein, and such vibrations cause the formation of sound waves in the air which are emitted from the diaphragm and are audible to the ear. Obviously only the sound waves formed by the outer, or as usually termed, front side C' of the diaphragm will be audible and the waves formed by the inner, or properly, rear side or back C'' of the diaphragm will be confined to the cavity formed between body member A and cap D. Accordingly there will be no cancellation of certain frequencies by the movement of out of phase sound waves from front to back of the diaphragm, as occurs where there is means of communication between opposite sides, and the frequency response is therefore substantially flat or level throughout its range. The effect is as though there were a baffle of infinite size such that no frequencies could possibly reach the back of the diaphragm in proper phase relation to cause cancellation.

Such flat frequency response is a disadvantage under some circumstances such as where the unit is used primarily for voice and communication work, or particularly where the unit is a part of a hearing aid device for use by the hard of hearing. In such cases it is very desirable to vary the frequency response to effectively accentuate desired frequencies by the reduction or cancellation of unwanted or useless frequencies. For example, most persons having difficulty in hearing have better perception at certain frequencies than at others, and the adjustment of the response of the unit to give maximum effect to the frequencies at which hearing loss is greater is obviously desirable. In accordance with my invention, therefore, I provide means for varying the baffle effect of the casing and cap upon the diaphragm C as will now be described.

The cap D is formed with a shoulder or ledge 10 adapted to bear against the margin of the diaphragm and press it against the end of the shell B, and to thus provide space 11 for vibratory movement of the diaphragm. I provide, then, a channel or groove 12 in this ledge at one point (or more) extending radially therein and communicating with the space 11 at the front of the diaphragm. This channel also communicates with a similar (or continuation) channel or groove 13 formed in the interior annular surface 14 of the cap D which contacts the cor-

responding annular outer surface 15 of the shell B. In this shell there is formed a radially extending opening 16 which registers at its outer end with the channel 13 and at its inner end communicates with the cavity back or at the rear of the diaphragm. At a point radially aligned with the opening 16 the cap D has in its flange or outer wall 17 a tapped opening or socket 18 opening into the channel 13 and in which is placed a threaded plug or screw 19. The screw may obviously be moved inward or outward in the opening 18 by a screw driver inserted through the open outer end thereof. The screw or plug 19 is preferably larger in diameter than the opening 16 or the width of channel 13 so that they may be completely closed off when the plug is screwed inward as seen in Fig. 1.

Essentially, then, the invention is seen to comprise an air passage, channel or vent, made up by the channels 12-13 and the opening 16, communicating at its ends with the opposite front and rear sides of the diaphragm C, and with means, formed here by the plug or screw 19, to open or close this passage and vary the effective capacity thereof. It is evident that when the plug 19 is screwed inward as far as possible the communication between front and rear of the diaphragm is entirely cut off and the baffle effect is infinite. As the plug is drawn outwardly the passage-way is gradually opened permitting the flow of air from front to back of the diaphragm in greater or lesser volume or degree as indicated in Fig. 3, to thus gradually reduce the baffle effect and accordingly vary the effective frequency response of the unit. Such adjustment may be readily carried out to any degree required and, since the plug 19 is carried wholly by the cap D, the removal of this cap for any reason will not affect the adjustment, once it is made.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a device of the character described, a vibratory diaphragm, a casing supporting the said diaphragm and having a portion enclosing one side of the diaphragm and isolating that side from the opposite side and thereby causing an infinite baffle effect, said casing having a passage-way connecting the opposite sides of the diaphragm, and means associated with the casing for opening and closing the said passage-way to control the flow of air from one side of the diaphragm to the other.

2. In a headphone of the character described, a casing, a diaphragm marginally supported in the casing and having its front side exposed but having its rear side enclosed by said casing, an air passage means formed in the casing and communicating at its respective ends with the front and rear sides of the diaphragm, and means for varying the effective size of the said air passage means to thereby vary the baffle effect of the casing upon sound waves emitted by the diaphragm.

3. In a headphone of the character described, a casing comprising a body member and a cap

member removably mounted thereon, a diaphragm supported by the casing in such manner as to be exposed at its front side and enclosed at its rear side, and air passage means for permitting the limited passage of air between front and rear sides of the diaphragm, the said air passage means being formed in part in the body member and in part in the cap member.

4. In a headphone of the character described, a casing comprising a body member and a cap member removably mounted thereon, a diaphragm supported by the casing in such manner as to be exposed at its front side and enclosed by the casing at its rear side, and air passage means for permitting the limited passage of air between front and rear sides of the diaphragm, the said air passage means being formed in part in the body member and in part in the cap member, and means carried by the cap member and operative to enter the air passage means to vary the effective size thereof.

5. In a headphone of the character described, a casing comprising a body member and a cap member removably mounted thereon, a diaphragm supported by the casing and enclosed at its rear side by said casing, the said cap member having an opening to partially expose the front side of the diaphragm, and the said body member and cap member having respectively an opening and a channel forming a means for conducting air between front and rear sides of the diaphragm.

6. In a headphone of the character described, a casing comprising a body member and a cap member removably mounted thereon, a diaphragm supported by the casing and enclosed at its rear side by said casing, the said cap member having an opening to partially expose the front side of the diaphragm, the said body member having an opening communicating with the rear side of the diaphragm, and the said cap member having a channel communicating with the front side of the diaphragm and adapted also to communicate with the said opening when the cap member is mounted upon the body member.

7. In a headphone of the character described, a casing comprising a body member and a cap member removably mounted thereon, a diaphragm supported by the casing and enclosed at its rear side by said casing, the said cap member having an opening to partially expose the front side of the diaphragm, the said body member having an opening communicating with the rear side of the diaphragm, the said cap member having a channel communicating at its respective ends with the said opening and with the front side of the diaphragm, and a plug threaded in the cap member and operative to adjustably open and close the said channel.

8. In a headphone of the character described, a casing including a body member having a recess in one side, a diaphragm mounted at one side over the recess and adapted when vibrated to transmit sound wave vibrations from both its sides, a cap member mounted over the other side of the diaphragm, and means in the body member and cap member providing communication for the passage of sound waves between the opposite sides of the diaphragm.

FRANK J. FALTICO.
